US00D914436S

(12) **United States Design Patent** (10) **Patent No.:** **US D914,436 S**
(45) **Date of Patent:** **** Mar. 30, 2021**

(54) **AIR DIFFUSER WITH FOOD PREPARATION POT**

(71) Applicant: **SHARKNINJA OPERATING LLC**,
Needham, MA (US)

(72) Inventors: **Aaron Michael Gill**, Boston, MA (US);
Chris Martin, Concord, MA (US);
Thomas Guerin, Boston, MA (US);
James Ridzon, Boston, MA (US)

(73) Assignee: **SHARKNINJA OPERATING LLC**,
Needham, MA (US)

(**) Term: **15 Years**

(21) Appl. No.: **29/653,863**

(22) Filed: **Jun. 19, 2018**

Related U.S. Application Data

(63) Continuation of application No. 29/653,847, filed on
Jun. 19, 2018.

(57) **CLAIM**

The ornamental design for air diffuser with food preparation pot, as shown and described.

DESCRIPTION

FIG. 1 is a perspective view of an air diffuser with food preparation pot, showing our new design;
FIG. 2 is a front elevation view thereof;
FIG. 3 is a rear elevation view thereof;
FIG. 4 is a side elevation view thereof;
FIG. 5 is another side elevation view thereof;
FIG. 6 is a top plan view thereof;
FIG. 7 is a bottom plan view thereof;
FIG. 8 is a cross-sectional view as taken along lines 8-8 of FIG. 6;
FIG. 9 is a cross-sectional view as taken along lines 9-9 of FIG. 6;
FIG. 10 is a cross-sectional view as taken along lines 10-10 of FIG. 6; and,
FIG. 11 is a cross-sectional view as taken along lines 11-11 of FIG. 6.

1 Claim, 7 Drawing Sheets
